(57)

CLAIM

The ornamental design for a cash register, as shown and described.

DESCRIPTION

1. Cash register
2. Cash register
- 1.1 : Front
- 1.2 : Back
- 1.3 : Left
- 1.4 : Right
- 1.5 : Bottom
- 1.6 : Top
- 1.7 : Perspective
- 1.8 : Perspective
- 2.1 : Front
- 2.2 : Back
- 2.3 : Left
- 2.4 : Right
- 2.5 : Bottom
- 2.6 : Top
- 2.7 : Perspective
- 2.8 : Perspective

The designs for intelligent cash registers that are mainly used for cash registering, printing receipts, etc.; design 1 is the basic design; the key design point of design 1 lies in the

(Continued)

shape of the product, and the reproduction that can best show the key design point is the perspective view of design 1.

1 Claim, 16 Drawing Sheets

(58) Field of Classification Search

CPC G07G 1/0018; H04W 52/0225; H04W 52/0254; H04W 8/22
